PACKAGE AND METHOD OF AND MEANS
FOR MAKING THE SAMEJoseph W. Fay, Villa Park, Ill., assignor to Peck-
O-Fun Co., Chicago, Ill., a corporation of Illi-
nois

Application November 13, 1936, Serial No. 110,672

13 Claims. (Cl. 93—12)

This invention relates to a package and the method of and means for making the same.

The particular embodiment of the invention which I shall describe hereinafter in connection with the drawings is a moisture-proof bag or package for marketing candied popcorn, candy, peanuts and other confections, foodstuffs, and the like, which are subject to the deleterious effects of moisture. It is to be understood, however, that the invention is not limited to use with the particular goods above referred to, but may be employed for marketing other goods as suitable or desired.

One of the objects of the present invention is to provide an improved package, and method of and means for making the same, adapted for expeditiously and inexpensively packaging the goods.

It is also an object of the invention to provide an improved bag or package of simple and inexpensive construction and which will effectively protect the goods from moisture. In this respect the bag or package of the present invention is particularly adapted for marketing small quantities of candied popcorn, peanuts, and other confections at low cost, but it is to be understood that the bag or package of the present invention is in nowise limited to such use.

Another object is to provide for sealing the bag by heat and pressure, and preferably by means of the moisture-proof substance on the bag material and without an inner carton for backing the flexible bag material. In its more limited aspects, this is accomplished by forming the bag about a rigid shaping form which constitutes a backing member enabling the desired sealing of the bag by heat and pressure.

Another object is to provide a method of and means for forming bags or packages of this sort at an increased rate, and, more specifically, a method of and means for making bags or packages wherein the bag or package making capacity is double the capacity of the waxed or paraffined paper wrapper forming capacity.

Another object of the invention is to provide a waxed or paraffined paper bag or package which is effectively sealed to protect the contents of the bag or package without the necessity for applying additional wax or paraffine to the bag or package after filling the bag with the desired contents and closing and sealing the same.

Another object of the invention is to provide a waxed or paraffined paper bag or package which may be sealed at the bottom, and elsewhere as desired, by additional wax or paraffine before

filling the bag with the desired contents and closing and sealing the top of the bag.

The present invention also provides a "Cellophane" bag which is sealed throughout by heat and pressure without the necessity of an inner carton instead of being glued as commonly done heretofore in the art, and still further, a double thickness bag as will hereinafter appear.

According to the present invention, the bag forming sheet is wrapped around a shaping form with the opposite edges of the sheet overlapping and the ends of the sheet extending beyond the ends of the form. The overlapping edges are sealed preferably by heat and pressure, and the narrow sides of the extending ends are folded in. The end flaps are folded closed with one end flap overlying the other end flap at each end of the wrapper and the closed end flaps are sealed, preferably by heat and pressure. If desired, where the bag is formed of waxed or paraffined paper, additional wax or paraffine may be applied to the ends of the wrapper thus formed, as by dipping, spraying, or the like.

Thereafter the wrapper is divided intermediate its ends into two corresponding open-ended bags or packages. These bags are filled through the open ends thereof, whereupon the open ends are closed and sealed, preferably by the application of heat and pressure. Where the bag is formed of waxed or paraffined paper, it is not necessary to apply additional wax after filling and closing and sealing the bags, and the capacity of the method and means is double the wrapper forming capacity.

Further objects and advantages and numerous adaptations of the invention will more fully appear from the following detailed description, taken in connection with the accompanying drawings, in which:

Figure 1 is a more or less diagrammatic side elevational view showing one embodiment of the method of and means for forming bags or packages in accordance with the present invention;

Figures 16 and 17 are perspective views showing another form of bag embodying the present invention.

According to the present invention, the bag is preferably formed of heavily waxed or paraffined paper, although "Cellophane" or any other suitable bag or package materials are contemplated within the scope of the present invention.

In fact, within certain aspects of the invention, the bag may be formed of ordinary paper, dipped, sprayed, or otherwise treated, preferably inside and outside, with wax, paraffine, liquid "Cellophane", moisture-proof lacquer or with any other chemical, chemical mixture or substance that will provide the desired seal, such bag being closed and then sealed with heat and pressure.

The first step is to wrap the sheet 5 of waxed or paraffined paper, "Cellophane" or other suitable material around a shaping form 6 with the edges 7 of the sheet 5 overlapping to form the seam 8 and the ends of the wrapper extending beyond the ends of the form. The opposite narrow sides of the extending portions of the wrapper 5 are folded in at 9 (Figure 7).

In Figures 1 to 4, inclusive, the wrapping of the sheet 5 around the form 6 and the forming of the folds 9 are accomplished on a table 10 (Figure 1) by any suitable or preferred means such, for example, as the means now commonly employed for wrapping similar sheets around waxed stiff paper board containers and the like.

The seam 8 is disposed downwardly on the table 10, and the form 6 with the wrapper thus folded is advanced to the left (Figure 1) over a hot iron 11 and between a pressure roller 12 and a compression belt 13. The hot iron 11, pressure roller 12 and compression belt 13 constitute heat and pressure means for sealing the overlapping

edges 7 together along the seam 8 by the wax, paraffine, or other substance, on the sheet 5, or by the "Cellophane" constituting such sheet or applied thereto. The form 6 constitutes a rigid backing which enables such sealing by heat and pressure along the seam 8, particularly without an inner carton for backing the flexible sheet. The compression belt 13 travels over suitable pulleys or sheaves 14.

The shaping form 6 with the sheet 5 as thus wrapped and folded thereon is then advanced as, for example, by mechanical advancing fingers or other suitable means from the table 10 onto an endless belt or conveyor 15 which is trained about pulleys 16 and travels in the direction indicated by the arrow 17 (Figure 1). Where the bag is formed of waxed or paraffined paper, melted wax, paraffine, or other suitable material is preferably sprayed at 18, as the wrapped forms 6 travel along with the movement of the conveyor 15, thoroughly over the inner surfaces of the extending flaps 19 and 19', and over at least the portions of the folds 9 which are subsequently covered by the flaps 19 and 19'. It is immaterial if, in spraying wax on the inner surfaces of the extending end flaps and folds of the wrapper, wax is also sprayed on the exposed ends of the form. It is to be understood that the wax or paraffine spraying devices are duplicated at opposite sides of the conveyor 15.

Beyond the spraying of melted wax at 18 and in the direction of movement of the conveyor 15, folding devices are provided at 20 to fold the bottom flaps 19' to closed position, and beyond these folding devices 20 a second set of folding devices at 21 fold the top flaps 19 to closed position overlapping the bottom flaps 19'. After leaving the folding devices at 21, the wrapped form with the ends of the sheet 5 as now folded closed, moves between heated irons 22, spring-pressed at 23. These heated and spring-pressed irons 22 seal the internally sprayed and closed flaps 19 and 19' by heat and pressure, the forms 6 again constituting rigid backings which enable such sealing of the flaps 19 and 19' by heat and pressure. The folding devices 20 and 21, and heat and pressure irons 22, are duplicated at opposite sides of the machine as shown in Figure 3 to perform the same operations at each of the opposite ends of the wrapper.

Thereupon, the wrapped forms move between pressure members 24 for holding the sealed end flaps 19, 19' closed, and into a longitudinally extending cooling chamber 25 supplied at its right hand end (Figures 1 and 3) with cold air or other suitable cooling means by a connected duct 26. The compression belt 13 preferably extends from position at one end over the pressure roller 12 to position at its opposite end over the heat and pressure sealing means at 22 and adjacent the duct 26. As the wrapped shaping forms pass successively through the chamber 25, the wax or paraffine is cooled and thoroughly set, and the wrappers 5 are now completely folded and sealed about the forms 6 and are of precisely the same shape as the forms.

It is appropriate here to point out that each of the shaping forms 6 is preferably completely encircled intermediate its ends by a groove 28, the purpose of which will now appear. These forms may be made of wood, metal, or any other suitable or preferred material. Where they are made of metal, they are preferably cored or hollowed out as shown at 29 (Figure 5).

Upon leaving the left hand end of the cooling

chamber 25 (Figure 1), the wrapped forms travel between upper and lower knife members 30 and 30', which knife members operate in the groove 28 to cut across the wide sides of the wrapper 5 intermediate the ends of the wrapper. Beyond the knife members 30 and 30' in the direction of travel of the upper run of the conveyor 15 radial fingers 32 on a rotary turning mechanism 33 (Figure 2) engage the wrapped forms successively as they reach the position for such engagement and turn the wrapped forms through approximately 90 degrees to position the same with their wide sides generally vertically and their narrow sides generally horizontally. The fingers 10 32, which turn in the direction indicated by the arrow in Figure 2, move up into engagement with the wrapped forms through a longitudinally extending opening 35 between the endless conveyor elements which are joined together by the transverse members 36, as shown in Figure 6, to form the conveyor 15.

As thus positioned by the turning mechanism 33, the wrapped forms move between a second pair of knife members 38 and 38' which operate 25 in the grooves 28 to cut across the narrow sides of the wrapper intermediate the ends thereof. This completely separates one half of the wrapper from the other half at a completely encircling cut intermediate the ends of the wrapper.

From the knife members 38, 38' and the turning mechanism at 33, the forms 6 carrying the two halves of the wrapper drop into a chute 40. At this position of the machine, girls or other operators may manually separate the two halves 35 of the wrappers from the forms. The opposite sides of the forms 6 may be provided with depressions 29'. The two halves of the wrapper are identical, and each now forms a bag, as shown at 42 in Figure 9, with an open top at 43, and 40 otherwise completely sealed along the seam 8 and at the bottom folds 9 and overlapping bottom flaps 19 and 19'.

Heat may be applied to the forms 6 to expedite removal of the bags therefrom, and it is to be understood that the bags may be removed from the forms mechanically or otherwise, instead of manually. For example, vacuum may be applied to the closed ends of the bags by suction cups or the like to remove the bags from the forms 6.

The bag forming process as thus far described is a two bag process in the sense that two bags are formed by the formation of each wrapper. The bag output is thus double the wrapper forming capacity of the machine. A practical embodiment of the invention may have a capacity of about 120 bags per minute, although wide variations in this capacity are contemplated within the scope of the present invention. In fact, insofar as the method of the present invention is concerned, the two bag forming aspect of the invention may be carried out by hand and at any desired rate.

Upon completion of the bags 42 to the extent thus far described, these bags are placed up-right upon an endless belt or conveyor 45 with their closed and sealed bottoms on the conveyor 45 and their open tops 43 directed upwardly. The placing of the bags 42 upon the conveyor 45 may be done manually, or it may be accomplished 65 mechanically and automatically in the operation of the machine in any suitable or desired manner.

The conveyor 45 operates over pulleys or sheaves 46 and travels in the direction indicated by the arrow 47 in Figure 2 to conduct the bags 70 to and beneath suitable filling mechanism for

the purpose of placing the desired contents in the bag.

In the embodiment of the invention shown in Figures 10 to 13, inclusive, the forms 6, which correspond to the forms 6 of the preceding embodiment of the invention, are fed ahead to the left manually or mechanically over a table 90 (Figure 10) and successively into position over a vertically reciprocating plunger 91.

The waxed or paraffined paper, "Cellophane", 10 or other suitable bag material, is fed to position and cut into strips 92 of the desired length, which are disposed beneath suitable guides 93. The plunger 91 lifts each form 6 up between the guides 93 as the forms are successively fed to 15 position upon the plunger 91, each form 6 carrying one sheet or strip 92 of wrapping material with it, and by cooperation with the guides 93, folding the extending sides of the sheet downwardly about the sides of the form. The form 20 6, with the sheet 92 thus folded thereon, is raised above the guides 93 sufficiently to permit the extending bottom finger 94 of the horizontally reciprocating plunger 95 to move beneath the bottom of the form and fold the lower portion of 25 the right hand side of the folded sheet 92 in beneath the bottom of the form 6. Continued movement of the plunger 95 brings the side 96 of the plunger into cooperation with the wrapper covered side of the form 6, and moves the form, 30 with the wrapper thereon, to the left (Figure 10) and onto a pair of transversely spaced rods or tracks 97. As the form with the wrapper thereon moves to the left and onto the rods 97, the lower portion of the left hand side of the folded sheet 35 92 is folded in beneath the bottom of the form 6, and preferably to position to overlap the in-folded opposite margin of the sheet.

Projections 98 on the plunger 95 engage the sides of the wrapper beyond the ends of the form 40 40 and produce folds similar to those shown at 9 in Figure 7 along one side of the wrapper, it being understood that other suitable means, such as projections beyond the ends of the form and in the path of movement of the projecting ends of 45 the wrapper to the left and onto the guides 97, engage the opposite side of the wrapper to produce folds similar to the folds 9 along the opposite side of the wrapper.

An advancing device 100, having depending fingers 101, is lowered and lifted to engage a series of the wrapped forms, five in the illustrated embodiment of the invention. This advancing device 100 is also moved back and forth generally lengthwise of the rods 97 to advance the forms 55 to the left (Figure 10) along the rods 97, each wrapped form being advanced a distance 102 (Figure 10) with each operation of the advancing device 100. Suitable lever mechanism at 103 operates the advancing device 100 in the manner 60 set forth.

As the forms, as thus far wrapped, are thus advanced, they move up the inclined portions 104 of the rods 97, and then down and along continuations of said rods 97, as shown in Figure 11. 65 An endless conveyor 105 operates over sheaves or sprockets 106 and 107, and beneath the lengthwise extending portions of the rods 97 as shown in Figure 11. This conveyor 105 has transverse members 108 of channel section which engage 70 the wrapped forms and feed the same along the rods 97 toward the left, as viewed in Figure 11.

Folding devices 109, in the path of travel of the opposite extending ends of the wrappers on the forms in their movement along the rods 97, 75

fold the flaps corresponding to the bottom flaps 19' of the previous embodiment to closed position, and beyond these folding devices 109 a second set of folding devices 110, also in the path of travel 5 of the opposite extending ends of the wrappers, fold the top flaps corresponding to the flaps 19 of the previous embodiment of the invention to closed position overlapping the bottom flaps 19'. After leaving the folding devices 110, the ends of 10 the wrapped forms with the ends of the wrappers as now folded closed thereon move between a pair of plates 112, one at each of the opposite sides of the machine. These plates 112 have openings 113 cored therein, and wax, paraffine, or other 15 suitable material as herein set forth, is delivered into the hollow interiors of these plates by tubes 114 leading from a suitable source 115 of wax, paraffine, or other suitable material. Longitudinal slits 116 are formed in the plates 112 in communication with the hollow interiors thereof, and open from the inner surfaces of these plates to permit the wax or other material to drip or flow onto and over the folded ends of the wrappers as the wrapped forms pass between the 25 plates 112.

Thereupon, the folded ends of the wrappers, which are now closed about the forms 6, move between heated plates 120, which may be spring-pressed or otherwise adapted to apply heat and 30 pressure to seal the closed ends of the wrappers to which the additional wax or other material has now been applied. A compression and guide member 121 guides and holds the wrapped forms down firmly upon the rods 97 in their movement 35 along the conveyor 105 as thus far described.

The wrapped forms, with the wrapper completely sealed about said forms by heat and pressure, thereupon move into a longitudinally extending cooling chamber 123 supplied, at its right hand end (Figure 11), with cold air or other suitable cooling means by a cold air supply nozzle 124. In their movement through the cooling chamber 123, the folded ends of the wrappers are held closed and sealed by compression belts 125, 40 one disposed along each of the opposite ends of the wrapped forms and trained at one end over sheaves 126 (Figure 11), and at their opposite ends over sheaves 127 (Figure 12). In passing through the cooling chamber 123, the sealed 45 wrappers are cooled and set, whereby all seams and folds are rendered moisture proof.

Upon leaving the left hand end of the cooling chamber 123 (Figure 12), the wrapped forms travel between upper and lower knife members 55 129 and 130, respectively. These knife members operate in the grooves 28 (Figure 5) in the forms 6 to cut across the wide sides of the wrappers, as in the preceding embodiment of the invention. A plate 131 preferably underlies the rods 97 at 60 and beyond the left hand end of the cooling chamber 123, as shown in Figure 12. Beyond the knife members 129 and 130 in the direction of travel of the wrapped forms and after the wrappers are cut across their wide sides, the wrapped 65 forms move over the upper end of a tube 132 which passes through the plate 131 intermediate the ends of the wrapped forms and discharges a blast of air into the cuts produced across the wide sides of the wrappers by the knife members 129 and 130. This blast of air loosens the wrappers 70 from the forms 6.

As the forms with the wrappers thereon leave the left hand end of the compression belt 125 (Figure 12), they drop down edgewise along the 75 downturned rods or tracks 97' and into position

ahead of a reciprocating plunger 135, with their wide sides disposed vertically instead of horizontally as in their travel up to this position. The plunger 135 advances the forms with the wrappers thereon to the left (Figure 12) along a pair of 5 transversely spaced rods or tracks 136. As thus advanced, the wrapped forms move between a second pair of knife members 139 and 140 which operate in the grooves 28 (Figure 5) to cut across the narrow sides of the wrappers intermediate 10 the ends thereof. This completely separates one half of the wrapper from the other half at a completely encircling cut intermediate the ends of the wrapper.

At this position, girls or other operators may 15 manually separate the two halves of the wrappers from the forms 6, the depressions 29' in the forms facilitating the desired gripping engagement of the fingers with the narrow sides of the bags or wrappers, and further facilitating handling of the 20 forms and removal of the bags therefrom. In this respect, the knife members 139 and 140, while sharp at their forward ends to cut the wrappers as above set forth, are preferably blunt or rounded at their opposite ends as shown at 142 (Figure 25 13), these blunt or rounded ends by their interlocking engagement in the grooves 28 holding the forms 6 against endwise displacement during removal of the two halves of the wrappers therefrom. 30

The two removed halves of the wrappers are identical, and each now forms a bag, as shown at 42 in Figure 9, with an open top at 43 and otherwise completely sealed along the seam 8 and at the bottom folds 9 and overlapping bottom 35 flaps 19 and 19'.

Upon removal of the bags from the forms 6, these forms 6 are placed upon an endless conveyor 145 which overlies the parts of the machine above set forth and travels in the direction 40 of the arrow 145' (Figures 10, 11 and 12) to return the forms 6 to the opposite end of the machine. At the right hand end of the machine (Figure 10), the conveyor 145 delivers the forms 6 to a curved track 146, and the forms slide down 45 this track to position upon the table 90 for the formation of bags thereon as already set forth. The track 146 may be formed of curved rods for holding the forms against sidewise and endwise displacement and for guiding the same down to 50 position upon the table 90. The conveyor 145 is trained at its opposite ends over sheaves or pulleys 147.

Ahead of the track 146 in the path of movement of the forms with the conveyor 145, I provide means at 148 for greasing the entire sides 55 149 (Figure 10) of the forms in their return movement. This greasing device may comprise a grease receptacle provided with a sponge, cotton, or the like, extending over the entire length of 60 the form for wiping grease over the entire surface 149 of the form in the movement of the form past such greasing device. While I refer to grease, any other substance may be applied to 65 the forms to prevent undesirable sticking or adhesion of the wrappers thereto.

Grease, or any other suitable or preferred substance, is also applied over the ends of the forms 6 for the same purpose, by a pair of greasing devices 150. These second greasing devices 150 are disposed at the lower end of the track 146, one at each of the opposite ends of the forms in their passage therebetween, and wipe the grease or other substance over the ends of the forms in the

passage of the same between these greasing devices.

Upon completion of the bags to the extent thus far described, these bags 42 are placed upon a suitable conveyor for the purpose of carrying them beneath suitable filling mechanism for the placing of the contents in the bag.

From the foregoing description, it will now be apparent that the bag shaping forms 6 constitute rigid backing members which enable sealing the bags by heat and pressure without the necessity for an inner carton for backing the flexible bag forming material and notwithstanding the flexible character of the bag material. This sealing of the bag by heat and pressure on a rigid form and subsequent removal, filling, closing, and sealing of the open top of the bag is an important aspect of the present invention, and so far as this aspect of the invention is concerned, the bag may be formed of waxed or paraffined paper, or of "Cellophane" or any other suitable or preferred moisture-proof material.

The bag 260, for example, shown in Figure 14 is similar to the bag shown in Figure 9, except that it is formed of "Cellophane". It is not glued, but is sealed throughout by heat and pressure in the manner herein set forth.

With the present invention, bags formed of "Cellophane" and the like may be sealed by heat and pressure, and thereby effectively rendered moisture tight throughout.

Another important aspect of the invention resides in the two bag process wherein the wrapper is closed and sealed about the form and then divided intermediate its ends into a pair of moisture-proof bags.

I further contemplate, within the scope of the present invention, making a double thickness bag as shown in Figure 15, the inner bag 265 being of ordinary paper, waxed paper, or other suitable material, and the outer bag 266 being formed of "Cellophane" or other suitable material, formed, folded, closed and sealed by heat and pressure as herein set forth.

A further embodiment of the invention consists, as shown in Figures 16 and 17, in placing the goods in a bag 300, as shown at 302, telescoping another bag 301 over the bag 300 (Figure 17), and then moisture-proofing the telescoping bags to make the same moisture-proof and seal the space therebetween. Where the two bags 300 and 301 are of plain paper or other suitable material, the moisture-proofing of the same, as by dipping or spraying suitable moisture-proof material thereover, renders the package moisture-proof. Where these bags 300 and 301 are made of "Cellophane" or other moisture-proof material, one bag is filled and then telescoped into the other bag as set forth, and then, instead of moisture-proofing the entire bags, it is only necessary to apply a moisture-proof material about the open end of the outer bag and the adjacent portion of the other bag to seal the bags together.

I do not intend to be limited to the precise details shown or described, nor do I intend to limit the use of the bags to any particular goods. Furthermore I do not intend to limit the invention to the precise order of the steps herein recited except as the same are expressly included in the appended claims.

I claim:

1. The method of forming moisture-proof packages which comprises closing a moisture-proof sheet around a shaping form to form a

closed wrapper, dividing the wrapper to form a pair of moisture-proof packages, and removing said packages from said shaping form.

2. The method of forming moisture-proof packages which comprises wrapping a moisture-proof sheet around a shaping form with the ends of the sheet extending from the form, joining the edges of the sheet, closing the extending ends of the sheet to form a closed wrapper, and dividing the wrapper intermediate the ends thereof whereby to form a pair of packages having open ends formed where the wrapper is divided.

3. The method of forming moisture-proof packages which comprises wrapping a sheet of waxed paper around a shaping form with the edges of the sheet overlapping and the ends of the sheet extending from said form, applying heat and pressure to the overlapping edges of the sheet to seal the same by the wax thereon, folding the extending ends of the sheet closed, applying heat and pressure to said closed ends to seal the same by the wax thereon, and dividing the wrapper intermediate the ends thereof whereby to form a pair of packages having open ends formed where the wrapper is divided.

4. The method of forming moisture-proof packages which comprises closing a moisture-proof sheet around a shaping form having a groove surrounding the same to form a closed wrapper, dividing the wrapper along the groove in said shaping form to produce a pair of moisture-proof packages, and removing said packages from said shaping form.

5. The method of forming moisture-proof packages which comprises wrapping a moisture-proof sheet around a shaping form having a groove surrounding the same with the ends of the sheet extending from the form, joining the edges of the sheet, closing the extending ends of the sheet to form a closed wrapper, and dividing the wrapper intermediate the ends thereof and along the groove in said shaping form whereby to produce a pair of packages having open ends formed where the wrapper is divided.

6. The method of forming a moisture-proof bag which comprises folding and completely closing a moisture-proof bag material about a rigid form, applying heat and pressure to the folds and seams of said bag material and against said rigid form to seal the same by the moisture-proof substance thereon, dividing the wrapper thus formed into a pair of moisture-proof bags and removing said bags from the form.

7. In a packaging machine, means for moving rigid forms wrapped in moisture-proof wrappers with the sides of said wrappers overlapping and sealed together and flaps extending from the ends of said wrappers, means along the path of movement of the wrapped forms for closing said flaps and sealing the same by heat and pressure and against said forms, and knife means for dividing the wrappers intermediate their ends into moisture-proof bags.

8. In a packaging machine, means for moving rigid forms wrapped in moisture-proof wrappers with the sides of said wrappers overlapping and sealed together and flaps extending from the ends of said wrappers, means along the path of movement of the wrapped forms for closing said flaps and sealing the same by heat and pressure and against said forms, knife means for cutting across one pair of opposite sides of the wrapper intermediate its ends, and second knife means for cutting across the other pair of opposite sides

75 70 75

of the wrappers to divide the wrappers into moisture-proof bags.

9. In a packaging machine, means for moving rigid forms wrapped in moisture-proof wrappers with the sides of said wrappers overlapping and sealed together and flaps extending from the ends of said wrappers, means along the path of movement of the wrapped forms for closing said flaps and sealing the same by heat and pressure and against said forms, knife means for cutting across one pair of opposite sides of the wrapper intermediate its ends, and second knife means for cutting across the other pair of opposite sides of the wrappers to divide the wrappers into moisture-proof bags, said last knife means having interlocking engagement with said forms to hold same against endwise movement in removing the bag from the forms.

10. In a packaging machine, means for moving forms wrapped in waxed paper with the sides of said wrappers overlapping and sealed together and flaps extending from the ends of said wrappers, means along the path of movement of the wrapped forms for applying additional wax to said flaps, means for closing said flaps and sealing the same by the wax thereon, knife means for cutting across one pair of opposite sides of the wrapper intermediate its ends, and second knife means for cutting across the other pair of opposite sides of the wrapper to divide the wrapper intermediate its ends into a pair of moisture-tight bags.

11. In a packaging machine, a conveyor for moving closed wrappers of generally rectangular

section, knife means for cutting across one pair of opposite sides of the wrappers in the movement of said wrappers on said conveyor, second knife means, and means for turning said wrappers through approximately 90 degrees for engagement of said second knife means with the other pair of opposite sides of the wrapper whereby to cut across said other sides and divide the wrapper intermediate its ends into two bags.

12. The method of forming bags which comprises closing a sheet around a shaping form to form a wrapper completely closed about said form and with the ends of the wrapper and the sides thereof shaped and positioned generally to conform with the shape and position of said ends and sides when the bags are filled, sealing the adjacent edges and the closed ends of the wrapper while the same is positioned on said form, and dividing the wrapper before removal from said form intermediate the closed ends to 20 form a pair of bags.

13. In combination, means for closing a sheet around a shaping form to form a wrapper completely closed about said form and with the ends of the wrapper and the sides thereof shaped and positioned generally to conform with the shape and position of said ends and sides when the bags are filled, means for sealing the adjoining edges and the closed ends of the wrapper while the same is positioned on said form, and means for dividing the wrapper before removal from said form intermediate the closed ends to 30 form a pair of bags.
